UNITED STATES PATENT OFFICE

LAUSIE F. ISAACKS, OF CHICAGO, ILLINOIS, ASSIGNOR TO TRANSPARENT TUBE COMPANY, OF CHICAGO, ILLINOIS, A CORPORATION OF ILLINOIS

METHOD OF APPLYING PRINTED MATTER TO TRANSPARENT SHEETS

Application filed May 12, 1930. Serial No. 451,566.

This invention relates to a method of printing on transparent paper, and has particular reference to a method of printing upon relatively thin transparent paper commonly used for wrapping purposes, which is transparent and the surface of which is smooth and glossy. In the usual method of printing on this characterized of paper, it is necessary to insert a sheet of porous paper, or paper having a relatively rough surface, between the sheets of transparent paper upon which the printing is applied. This operation entails an excessive amount of time and labor, and it is also necessary to delay for several hours while the ink is drying before the paper may be handled or used.

An object of the present invention resides in a method of printing upon transparent paper of the kind mentioned, in which the necessity of inserting blotting or porous sheets until the ink has dried, is entirely avoided, and the paper is ready for handling and use immediately upon the completion of the method of this invention. A more detailed object resides in applying the printing upon paper of the same character as the paper constituting the body of the wrapper or main sheet, and causing the two sheets to adhere to each other through the medium of the ink employed in the printing, or an additional adhesive. A more particular object is the provision of a method in which the printing is applied to a marginal edge of a sheet of transparent paper and the margin then folded to render the printing visible. It will be understood that the method of printing embodied in this invention is adaptable to a wide variety of purposes, including the printing of transparent paper for the wrapping of small articles, as well as tubular wrappers for cigars or similar articles, and sacks or bags of various sizes and for various purposes.

Other objects will appear hereinafter.

The invention consists in the combinations and arrangements of method steps herein-after described and claimed.

The invention will be best understood by reference to the accompanying drawings, forming a part of this specification, and in which:

Fig. 1 is a plan view of a sheet of transparent wrapping paper with a separate strip of paper of the same character with printing thereon applied in accordance with the present invention;

Fig. 2 is an edge view of the papers shown in Fig. 1;

Fig. 3 is a reverse face view of the ink receiving strip shown in Fig. 1;

Fig. 4 is a view of a modified adaptation of the invention, in which printing is applied to one marginal edge of a sheet of paper rolled to provide a tube, with one corner withdrawn;

Fig. 5 is an edge view of the structure shown in Fig. 4;

Fig. 6 is a modified adaptation of the method of forming a tubular container wherein an additional adhesive is applied because of the relatively small surface covered by the ink used in printing;

Fig. 7 is an edge view of the structure shown in Fig. 6;

Fig. 8 shows a further alternative method of carrying out the invention wherein printing is applied to the marginal edge of a sheet of paper;

Fig. 9 is a view similar to Fig. 8, wherein the marginal edge has been folded; and

Fig. 10 is an edge view of the form shown in Fig. 9.

As illustrated in the drawings, the preferred method of the invention comprises the application of printed matter to a sheet of transparent paper 12. Where the surface covered by the ink is relatively small an additional adhesive 13 is preferably applied, and then the strip or sheet 12 is brought in contact with a second sheet 14 of a like character of paper, with the ink or adhesive contacting on the surface of the sheet 14. By this method, because of the transparency of the paper, the outline of the printing will be plainly visible through the reverse side of the sheet 12 from that shown in Fig. 3, or as shown in Fig. 1.

Referring to the form shown in Figs. 4 and 5, the printing is applied to the edge surface 15 of a sheet of transparent paper 16, after which the sheet may be rolled to the form shown, and because of the relatively

large surface covered by the ink 17, additional application of adhesive is rendered unnecessary. If desired, glue or other extraneous adhesive may be added to the ink for printing purposes to increase the adhesive properties of the ink, although in many cases the usual printing ink will cause the contacting surfaces to tightly adhere, particularly where a thin, pliable paper is used. As indicated, after the roll is completed, the printed subject matter is clearly visible from the reverse side of the sheet from that upon which the printing has been applied, and in these two adaptations described a direct reading plate or setting of type is used. It will be understood, however, that the printing may be applied, if preferred, to the covered surface, inasmuch as the outline will be clearly visible through the covering sheet.

20 In the form shown in Figs. 6 and 7, because of the relatively small area covered by the ink, an additional adhesive 18 is applied along the margin of the overlapping portion.

In the adaptation of the method shown in Figs. 8, 9 and 10, a marginal portion 19 of a sheet of transparent paper 20 receives the printing and the marginal paper is then folded to the position shown in Fig. 9, with the printed outline visible from the exterior through the folded marginal portion 19. The method permits of employment in the application of printing to transparent paper for any desired purpose, and the paper is available for use immediately upon completion of the operations of the method, whereas the time consumed and expense involved in the previous methods have been so great that printing has not been applied to the character of paper disclosed except in rare instances.

40 It is obvious from the foregoing that the method above described is equally applicable to sheets which are not totally transparent, but are more nearly translucent; also to sheets which are not commonly designated as paper, such as cellophane and the like.

45 While I have illustrated and described the preferred method for carrying my invention into effect, this is capable of variation and modification without departing from the spirit of the invention. I, therefore, do not wish to be limited to the precise details of method steps set forth, but desire to avail myself of such variations and modifications as come within the scope of the appended claims.

50 1. The method of applying printed matter to a substantially transparent sheet which comprises printing with adhesive ink upon a receiving surface and then placing said transparent sheet over the freshly printed surface to cause said surface and sheet to adhere by reason of the adhesive properties of the ink used in the printing.

55 2. The method of applying printed matter

to a substantially transparent sheet which comprises printing with adhesive ink upon a portion of a receiving surface, applying adhesive to another portion of said surface, and then placing said transparent sheet over the freshly printed surface to cause the surface and sheet to adhere by virtue of the united properties of the ink and adhesive.

3. The method of applying printed matter to a substantially transparent sheet which comprises printing with adhesive ink upon another substantially transparent sheet, and placing said first sheet over the freshly printed surface of the second to cause both of said sheets to adhere by reason of the adhesive properties of the ink used in the printing.

4. The method of applying printed matter to a substantially transparent sheet which comprises printing with adhesive ink upon a portion thereof, and then placing a second portion of the sheet over the first freshly printed surface of the portion to unite the portions by reason of the adhesive properties of the ink used in the printing.

5. The method of applying printed matter to a substantially transparent sheet which comprises printing with adhesive ink upon one side of the sheet, and folding said sheet to bring the printed surface into contact with a remaining portion of the sheet, whereby the contacting portion of the sheet will be caused to adhere and the printed matter disposed between the portions, by reason of the adhesive properties of the ink.

6. The method of applying printed matter to a substantially transparent sheet which comprises printing invertedly with adhesive ink upon a portion of the sheet, and folding said printed surface into contact with a remaining portion to cause the portions to adhere by reason of the adhesive properties of the ink.

7. The method of applying printed matter to a substantially transparent sheet which comprises printing with adhesive ink upon a portion thereof, applying adhesive to said portion, and causing a second portion of the sheet to be united to the printed surface by virtue of the united properties of the ink and adhesive.

In testimony whereof I have signed my name to this specification.

LAUSIE F. ISAACKS.
